PROCESS FOR RETURNING AND RECOVERING HEAT FROM VAPORS PRODUCED
IN A PROCESS OF DECOMPOSING PETROLEUM OILS
Filed Sept. 26, 1927

Filed Sept. 26, 1927

UNITED STATES PATENT OFFICE

ARCHIE L. STROUT, OF BERKELEY, CALIFORNIA, ASSIGNOR TO STANDARD OIL COMPANY OF CALIFORNIA, OF SAN FRANCISCO, CALIFORNIA, A CORPORATION OF DELAWARE

PROCESS FOR RETURNING AND RECOVERING HEAT FROM VAPORS PRODUCED IN A PROCESS OF DECOMPOSING PETROLEUM OILS

Application filed September 26, 1927. Serial No. 221,920.

This invention relates to the art of decomposing or cracking oils, such as petroleum oils, and has to do more particularly with a cracking process commonly known as the vaporization type wherein the charging stock, after passage through the heating zone in which the oil is raised to the desired cracking temperature, is passed into an enlarged reaction chamber where vaporization takes place for the separation of the lower boiling point constituents from those of higher boiling point.

Heretofore, in the practice of the vaporization method of cracking oils as above outlined, there has been evolved from the vaporization chamber not only those constituents comprising the desired low boiling point or gasoline-like products, but in addition thereto, so much of the heavier or higher boiling point ingredients that there is left in the vaporization chamber either only coke or a heavy liquid residuum of low A. P. I. gravity, usually at about 9° A. P. I. gravity or such as to make it of suitable fuel oil viscosity. When the process is thus practiced the total vaporized material from the vaporization chamber is passed to a dephlegmating tower in which the heavier vapors are condensed from the gasoline-like or desired low boiling point ingredients, and such heavy constituents therefrom recycled as a reflux from the tower back through the heating coils and into the vaporization chamber.

In the co-pending application of Ralph A. Halloran and Archie L. Strout, filed March 21, 1927, Serial No. 176,990, process of decomposing relatively high boiling point oils into relatively low boiling point oils, there is described a type of cracking process of the vaporization type in which, in order to secure a substantial reduction in the quantity of coke formed in the process and substantial reduction in the sediment content of the liquid residuum produced in the process, as well as other advantages, the liquid in the vaporization chamber is maintained at an A. P. I. gravity several degrees higher than the gravity of the residuum to be formed in the system and in fact but slightly less in A. P. I. gravity than that of the feed oil

charged to the system. In order to obtain a high yield of gasoline-like or low boiling point constituents, it is necessary that the lower boiling point oils which are contained within this liquid thus withdrawn from the vaporization chamber, and which are useful for further cracking, be distilled therefrom and recycled through the process. It is the practice of said co-pending application thus to separate and use such lower boiling point constituents from this liquid withdrawn from the vaporization chamber.

In order to distinguish between the two stages of distillation which take place in a system of this type it will be understood that throughout the following discussion the vaporization chamber refers to the chamber into which the oil is discharged from the heating zone of the system and wherein the produced low boiling point or gasoline-like constituents are evolved as vapors. Of necessity there will be evolved along with said vapors the vapors of certain heavier constituents, thus making it necessary to fractionate these vapors so that the gasoline-like constituents may be separated from the heavier constituents. The term dephlegmator as used herein will be restricted to refer only to the fractionating equipment wherein this separation takes place. The term reflux will be restricted to the condensate obtained in said dephlegmator and returned to the heating zone. The material obtained by the condensation of vapors evolved during the distillation of the liquid withdrawn from the aforesaid vaporization chamber will be referred to as cycle stock and the vapors condensed to give said cycle stock will be termed cycle stock vapors. (It will be noted that both the said cycle stock and the said reflux may be returned to the heating zone of the system.) The bottoms remaining from the evolution of the cycle stock vapors will be termed residuum as distinguished from the bottoms withdrawn from the aforesaid vaporization chamber, which latter material will be designated as heavy liquid from the vaporization chamber.

In order to completely condense the cycle stock vapors, it is generally necessary that they be cooled to about 250° to 300° F. In

order to provide an economical operation of the cracking process in the use of heat, which economy will be reflected in fuel saving, it is necessary to conserve the heat of vaporization of the cycle stock vapors and to utilize this heat for the purpose of preheating the fresh feed oil to the cracking process.

Heretofore, in attempts to preheat feed oil of a cracking system, the common practice has been to utilize as far as practical heat exchangers so constructed that the liquid feed oil to be heated passes through closed passages in contact with the opposite walls of which is the medium to be cooled. Heat exchangers for this purpose are expensive to build and maintain. These, together with various other disadvantages, result in the fact that comparatively few heat exchangers are successfully employed to effect economy in connection with cracking apparatus.

In another co-pending application of A. L. Strout filed April 25, 1927, Serial No. 186,307, process of decomposing relatively high boiling point oils into relatively low boiling point oils, is described a process by which the recovery of the heat of the cycle stock vapors may be accomplished by transfer of heat to the fresh feed stock to be processed. This is done by the use of direct contact between the vapors of the oil to be recycled and the fresh oil.

In order to maintain economical operation it is necessary not only that the heat of the cycle stock vapors be preserved, but it is also necessary to conserve the heat in the vapors from which the reflux material is formed in the dephlegmator. In order to form the desired amount of reflux it is necessary that there be employed a cooling medium, the temperature of which may vary within certain limits depending upon the quantity of material so used. The present invention comprehends a process in which the heat of the cycle stock vapors may be recovered and imparted to the feed oil while at the same time using the heated feed oil and the resulting cooled cycle stock material, or different portions thereof, to maintain a cooling medium in the dephlegmator sufficient to form the desired reflux.

An object of the present invention is to provide a method or process for recovering the useful heat in a vaporized oil which is to be condensed and recycled to a cracking process, and a particular object of the present invention is to provide a method by which the recovery of the heat of the cycle stock vapors may be accomplished by transfer of heat to the fresh feed stock to be processed.

Another object of the present invention is to provide a method for efficiently recovering the heat of the cycle stock vapors, which employs the use of direct contact between the

vapors of the oil to be recycled and the fresh oil.

Another object of the present invention is to provide a method for condensing and recovering the heat of the cycle stock vapors using condensed cycle stock and fresh feed oil for this purpose, and using this combined cycle stock and feed oil, or a part of it, as a refluxing agent in the dephlegmating tower of the system.

Another object of the present invention is to provide a process of the class described in which the necessity for a multiplicity of recycling pumps and condensing and exchanging equipment is avoided.

Another object of the present invention is to provide a method for recovering the heat of the cycle stock vapors and the substantial condensation thereof by direct contact with a portion of the fresh feed oil, and by pre-cooling such hot cycle stock vapors by passage through a closed type heat exchanger countercurrent to the commingled feed stock and condensed cycle stock.

By the process of the present invention the oil to be cracked is passed through a heating coil where it is raised to a high temperature and pressure and then passed into a vaporization chamber where vapors are allowed to separate. These vapors then flow through a dephlegmator to a water-cooled condenser and receiving tank, all held at super-atmospheric pressure. The liquid withdrawn from the vaporization chamber is permitted to evaporate in part by releasing the pressure. The portion which fails to evaporate at this reduced pressure is withdrawn from the system as low-sediment residuum. The vaporized portion (i. e. the cycle stock) is passed through a closed heat exchanger where it gives up a part of its heat and where, as a consequence, some of it is condensed. This cycle stock then enters a chamber in which the vaporous portion is contacted with and condensed by a spray of cool feed stock. Combined feed stock and condensed cycle stock are pumped from the bottom of the aforementioned chamber through a closed passage in a heat exchanger, in contact with the opposite walls of which is the hot cycle stock vapor. The mixed feed and cycle stock is thereby further raised in temperature and flows back to the heating coil to be again subjected to cracking conditions.

The present invention may be better understood and comprehended in its various aspects in connection with the description of a process comprising an embodiment of the invention, by reference to the accompanying drawings which illustrate an apparatus in which a process embodying the invention may be performed. For this purpose there is hereinafter described a process embodying the present invention as carried out with

the apparatus illustrated in the accompanying drawings.

In the drawings, the apparatus is illustrated in diagrammatic elevation.

5 In the drawings, 1 represents a heating coil set in a furnace 2. In this coil the oil is raised to the desired decomposing temperature. Any decomposing temperature may be employed, a particularly suitable temperature 10 being from 850° to 890° F. when processing a gas oil fraction of California base oil. The temperature may be modified, depending upon the character of oil processed as well as the quantity and quality of the products 15 to be produced. It is then passed through line 3 into a vaporization and reaction chamber 4.

The pressure employed within the vaporization chamber will depend on the oil treated 20 and the amount of decomposition and vaporization of the heavy oils desired, but will generally range from 200# upwards, per square inch. From the vaporization chamber 4 the vapors pass through vapor line 5 into a 25 dephlegmating tower 6 which may be one of several different and suitable types. In this dephlegmating tower the desirable lighter or gasoline-like constituents will be separated from the heavier constituents and will pass 30 in vapor form through line 7 and thence through suitable condensing apparatus such, for example, as condenser coil 8. The condensate thus formed then passes through line 31 into receiving drum 9 where any relatively 35 fixed or incondensable gas is permitted to separate therefrom. This gas may be led off through valve 11 and line 10 and conducted from the system. The condensed gasoline-like or low-boiling point constituents will 40 pass through line 12 provided with valve 13 for further treatment or to suitable storage (not shown in the diagram).

The liquid oil withdrawn from evaporator 4 passes through pressure release valve 15 45 thence through line 14 and is discharged into vessel 16. The release of pressure through valve 15 is as a rule sufficient to permit of the vaporization from the hot liquid residuum, immediately upon its discharge into vessel 50 16, of a substantial quantity of the volatile ingredients thereof. The vapors thus evolved will comprise a quantity of material whose boiling points are higher than those of the constituents vaporized in the vaporization chamber 4. However, this material may be 55 used as a cycle stock for further cracking. When the release of pressure through valve 15 is not to atmospheric then a suitable pressure on the distillation element 16 is maintained by means of valve 32 located beyond the condensing equipment on line 30, the necessary valves being also provided on the liquid draw-off lines. By varying the pressure 60 on vessel 16 the quantity of vapor evolved and the consequent grade of fuel oil 65

residuum withdrawn from the system may be varied and controlled. The residuum thus formed is withdrawn through line 17 provided with valve 18. It will be understood that heat may be applied in any suitable manner to the material undergoing vaporization in vessel 16 and that if desired open steam may also be employed therein to assist in the evolution of the cycle stock vapors and that 70 vacuum may also be employed, if desired. 75

In the method of the present invention these cycle stock vapors are passed through line 19 thence through a suitable type of closed, and preferably insulated, heat exchanger 20, in which they give up a part 80

of their heat. In practice the temperature of the vapors may be reduced, for example, about 300° F. Consequently, the material flowing through line 19 out of the heat exchanger 20 will be partly vapor and partly 85 liquid. The temperature of this cycle stock is so reduced in the heat exchanger that at the low pressure of the cycle stock it may be directly contacted with the feed oil to the system without substantially vaporizing such 90 feed oil. All of this cycle stock passes into the lower part of a condensation vessel 21, where the remaining vapors are condensed by contact with cool feed oil introduced, preferably in the form of a spray, through line 95 22 and valve 23, in the upper portion of the vessel 21. The combined feed stock and condensed cycle stock runs to the bottom of the condensation vessel and is removed through line 25 entering the suction side of a pump 100 100 26 by which it is forced through the above described heat exchanger 20 in a direction countercurrent to the flow of hot cycle stock vapors in line 19. By this means heat transfer is effected from the hot vapors to the 105 liquid in line 25, raising the temperature of the latter, and partially vaporizing it. The material in line 25, after passing through the exchanger, re-enters the cracking system at an appropriate point. This may be, for ex- 110

ample, the base of the dephlegmator 6, in which case it mingle with the refluxed oil from 6 and is withdrawn through line 28 by a pump 29 and forced into the heating coil 1, completing the cycle. In order to bring about the desired refluxing in dephlegmator 6 it may be advisable to divert a part of the cold feed oil from line 22 through line 27, valve 24, and pump 36 and introduce it, in spray form, into the tower 6. In practice this is found to be quite feasible, since not all of the feed is required to completely condense the cycle vapors in the chamber 21. 115

Instead of using a part of the cold feed to reflux cracked vapors as described, it may be 120 preferable to put the entire amount of feed into the vessel 21, and divide the material in line 25, causing part of it to flow through the exchanger 20 as shown, and the remainder to enter the tower 6 through valve 34 and line 130

35 as refluxing agent. Or the entire amount of feed oil may be put into the vessel 21 and all of the combined feed and cycle stock caused to flow through the exchanger 20. Upon flowing out of the exchanger it may then be used as a whole or in part as a refluxing agent in the tower 6.

Various other modifications fall within the scope of this invention. For example, a part of the condensed naphtha as received in tank 9 may be returned to the vapor outlet of the tower 6 through line 33 to assist in fractionation. Again, the preheated feed and condensed cycle stock in line 25 may be run into line 28 directly, or may be run into the tower 6 at a point considerably above the base. The temperature of the stock will largely indicate where it should be returned to the system.

20 As an example of the operation of the herein described process, Southern California gas oil was heated in the coil 1 to 860°-870° F. The temperature of the vapors out of the vaporization chamber 4 was found to be in one case about 340° F., while the temperature of the unvaporized oil from the bottom of 4 was about 740° F. A pressure of 275 lbs. per square inch was carried on the system. At the valve 15 this pressure was released to atmospheric. The vapors leaving the vessel 16 were then at about 685° F. In their passage through the exchanger they were cooled to about 390° F. The feed oil at 70° F. introduced into vessel 21 through line 22 condensed all of the cycle stock, and the temperature of the mixed feed and cycle stock out of vessel 21 was about 150° F. This stock (line 25) was then divided. A part was put into tower 6 and the remainder was passed through the exchanger 20. In so doing its temperature was raised to about 500° F. The combined reflux oil, feed oil and cycle stock flowing through line 28 was then found to be about 750° F. It was thus necessary to raise the temperature of the oil flowing through the coil 1 only 110°-130° F.

An idea of the comparative quantities of oil handled in his process, in the example above described may be had from the statement that 43 parts of feed oil per hour were supplied through line 22, while 30 parts of cycle stock (considered as liquid) per hour passed through line 19, and 200 parts per hour passed through line 28 and coil 1. The gravity of the feed stock was 25° A. P. I., that of the residuum (line 17) was 10° A. P. I., and that of the naphtha received in drum 9 was 54° A. P. I. No heat was lost from the system except that carried by the residuum flowing through line 17 and that absorbed in condensing the naphtha (cooler 8).

It is to be understood that the figures quoted above serve merely to illustrate a typical operation of the process, and may vary

widely in other instances. A great deal will depend upon the quality of feed stock used, the yield and gravity of naphtha desired and the gravity of residuum required.

It is possible that the process may be operated to produce along with cycle stock vapors some vapors of naphtha or of an intermediate boiling point oil. In the case of naphtha vapors which are not condensed in vessel 21 it may be preferable to allow them to escape through line 30 and valve 32, leading to a condenser not shown. Such condensed naphtha may then be run into the body of naphtha coming from the drum 9, or it may be returned to an appropriate point in the tower 6 to serve as reflux material. The same disposition of an intermediate oil may be made, or it may be separately condensed and collected. Whenever it is desired to prevent the return to the cracking zone of those constituents of the cycle stock which come within the naphtha boiling point range, or whenever it is desired to remove any intermediate boiling point constituents, it is only necessary to allow the temperature at the vapor outlet of condensing chamber 21 to rise. This is accomplished by reducing the amount of feed oil entering the chamber through line 22 and valve 23.

An advantage of the present process lies in the fact that only one pump (26) is needed to recirculate the cycle stock. This pump will be required to handle only liquid material and at a moderate temperature.

Another advantage is derived from the fact that the precooling obtained by cycle vapors in the exchanger 20 serves to condense a part of the cycle stock. This condensate runs directly to the bottom of the vessel 21 and is removed from the condensing chamber thus facilitating the complete condensation of the remaining vapors by the spray of cool feed oil.

If instead of the closed exchanger shown, a jet condenser or any form of direct contact exchange were employed, a part of the feed oil and condensed cycle stock would be re-vaporized and would mingle with the vapors going to the final condenser 21, thus imposing a greater burden upon the condensation operation therein. With apparatus as described, however, the amount of vaporization which takes place in the combined feed and cycle stock flowing through line 25 in its passage through the heat exchanger 20 is immaterial.

It is to be observed that the method of condensation and heat exchange employed in the process of the present invention is applicable only to materials of the nature of petroleum oil, i. e. composed of a number of substances having different boiling points. It is not applicable to pure substances such as water (and steam).

While the form of process herein described

is well adapted for carrying out the objects of the present invention, it is understood that various modifications and changes may be made without departing from the invention and the invention includes all such modifications and changes as come within the scope of the appended claims.

I claim:

1. A process of decomposing oils into relatively lower boiling point oils which includes, heating the oils to a decomposing temperature, passing the oils into a vaporization chamber under a superatmospheric pressure, removing from said chamber part of the oils as vapors and part of the oils as liquid, releasing pressure from said liquid oils and vaporizing therefrom the more volatile constituents, partially cooling and condensing the vapors to a temperature below that at which said vapors will vaporize substantial portions of fresh feed oil when admixed therewith, by passing the vapors into indirect contact with the cooling medium, then passing such partially cooled and condensed vapors into direct contact with the feed oils of the system so as to further condense the vapors in a zone wherein no substantial vaporization of the feed oil takes place, applying an increased pressure to the feed oil and commingled condensate, utilizing the feed oil and commingled condensate as a cooling medium in the aforementioned operation of cooling and condensing said vapors, whereby the feed oil and commingled condensate is raised in temperature sufficiently high to substantially vaporize gas oil unless such increased pressure is imposed thereon, and finally passing the feed oil and commingled condensate to the heating zone.
2. A process of decomposing oils into relatively lower boiling point oils which includes, heating the oils to a decomposing temperature, passing the oils into a vaporization chamber under superatmospheric pressure, removing from said chamber part of the oils as vapors and part of the oils as liquid, releasing pressure from said liquid oils and vaporizing therefrom the more volatile constituents, partially cooling and condensing the latter vapors by subjecting them to indirect contact with the cooling medium, then directly contacting such partially condensed vapors with the feed oils of the system, then applying an increased pressure to the feed oil and commingled condensate, utilizing the feed oil and commingled condensate as a cooling medium in said aforementioned cooling and condensing operation, whereby the feed oil and commingled condensate is raised in temperature sufficiently high to substantially vaporize gas oil unless such increased pressure is imposed thereon, and finally passing the feed oil and commingled condensate to the heating zone.
3. A process of decomposing oils into rela-

tively lower boiling point oils which includes, heating the oils to a decomposing temperature, passing the oils into a vaporization chamber under super-atmospheric pressure, removing from said chamber part of the oils as vapors and part of the oils as liquid, releasing pressure from said liquid oils and vaporizing therefrom the more volatile constituents, partially cooling and condensing said latter vapors by indirect contact with the cooling medium, then directly contacting the partially condensed vapors with the feed oil in the system, utilizing the feed oil commingled with the thus condensed oils as said cooling medium, whereby the temperature of the feed oil and the thus condensed oils is raised high enough to vaporize gas oil unless additional pressure is imposed thereon, imposing such additional pressure, and passing the feed oil and commingled condensed oil to the heating zone together with any portion of said oils which may be vaporized in said indirect heat transferring operation.

4. A process of decomposing oils into relatively lower boiling point oils which includes, heating the oils to a decomposing temperature, passing the oils into a vaporization chamber under super-atmospheric pressure, removing from said chamber a part at least of the oils as liquid, releasing pressure from said liquid oils and vaporizing therefrom the more volatile constituents, partially cooling and condensing such vapors by subjecting them in a heat transferring zone to an indirect contact with the cooling medium until they may be contacted directly with the feed oil of the system without substantially vaporizing such feed oil, then passing such partially cooled and condensed vapors into a contacting zone in which they are directly contacted with the feed oils of the system so as to further condense the vapors in a zone where no substantial vaporization of the feed oil takes place, applying an increased pressure to the feed oil and commingled condensate, utilizing such commingled feed oil and condensate as a cooling medium in said heat transferring zone, whereby the feed oil and commingled condensate is raised in temperature sufficiently high to substantially vaporize gas oil unless such increased pressure is imposed thereon, and passing the feed oil and commingled condensate from said heat transferring zone together with any portion thereof vaporized in said zone to the heating zone.

5. An apparatus for decomposing oils into relatively low boiling point oils which comprises, a heating coil, a vaporization and reaction chamber connected to receive oils from said heating coil, means for withdrawing vapors from said vaporization and reaction chamber, means for withdrawing liquids from said vaporization and reaction chamber, means for vaporizing the liquids withdrawn from said reaction chamber under

- reduced pressure, a heat exchanger receiving said vapors, a contact chamber wherein said vapors partially condensed from said heat exchanger may be contacted with the feed oil of the system, means for applying an increased pressure to the said oil and condensate in said contact chamber and passing the same into said heat exchanger, said heat exchanger being operative to raise the temperature of the feed oil high enough to vaporize gas oil unless pressure is imposed on the feed oil therein, and means for passing the oils from said heat exchanger to said heating coil.
6. A process of decomposing oils into relatively low boiling point oils which includes heating the oils to a decomposing temperature, passing the oils into a vaporization chamber under super-atmospheric pressure, removing from said chamber part of the oils as liquid and part of the oils as vapor, releasing pressure from said liquid oils and vaporizing therefrom the more volatile constituents, partially cooling said vapors by indirect contact with the cooling medium in one heat exchanging zone, then passing the vapors to a separate zone in which the vapors are directly contacted with feed oil to the system, utilizing the feed oil commingled with the thus condensed oil as said cooling medium in said indirect heat exchanging zone, whereby the feed oil and commingled condensed oils are brought to a higher temperature in the indirect heat exchanging zone than in the contacting zone, imposing super-atmospheric pressure upon the feed oil and condensed oils before it is passed into the indirect heat exchanging zone, and finally passing the feed oil and condensed oils to the first mentioned heating zone.
7. A process of decomposing oils into relatively lower boiling point oils which includes heating the oils to a decomposing temperature, passing the oil into a vaporization chamber under superatmospheric pressure, removing from said chamber part of the oils as vapors including the produced relatively lower boiling point oils and part of the oils as liquid, releasing pressure from said liquid oil and vaporizing therefrom the more volatile constituents, partially cooling and condensing the latter vapors by subjecting them to indirect contact with a cooling medium whereby the same are cooled sufficiently so that they may be contacted at atmospheric pressure with the feed oil of the system without materially vaporizing the feed oil, then so contacting said vapors with the feed oils of the system thereby condensing the same, passing feed oils and condensed oils to said indirect heat exchanging operation to operate as a cooling medium, superatmospheric pressure being imposed thereon, whereby said oils are raised to a higher temperature than the temperature of the oils in the zone where the feed oil is contacted with the vapors from

the liquid withdrawn from the vaporization chamber, and finally passing the feed oil and condensed oils to the heating zone.
